SILENCER FOR INTERNAL COMBUSTION ENGINES

Giorgio Bacchetti-Righetti, Rome, Italy

Application September 18, 1935, Serial No. 41,154
In Italy June 3, 1935

1 Claim. (Cl. 181—66)

Subject matter of this invention is a silencer for internal combustion engines the fundamental feature of which consists in imparting, by helical surfaces and ducts, to the exhaust gases an intermittently inverted rotary movement so as to produce a dynamic resistance to the flow of said gases which, though being quite free in their propulsive expansion movement, are guided by the spiral way and discharged from the exhaust with diminished velocity and detonation.

With my improved silencer, to the increase of number of revolutions of the engine corresponds an increase of silencing without inadmissible increase of losses of efficiency of engine being caused by silencer.

One of the objects of my present invention consists in providing a silencer which besides having a high efficiency increasing with the number of revolutions of engine, permits of a minimum counterpressure to exhaust as compared with usual silencers of equal efficiency.

In the structure of silencer the volume, the number of helices and the pitch vary according to the efficiency and number of cylinders of the engine with which it is to be used.

The invention is shown by way of an illustrative, not limitative, example in the annexed drawing, in which:

Fig. 1 is a longitudinal section of the silencer subject matter of invention, with parts in elevation, and

Fig. 2 is a section on line II—II of Fig. 1.

With reference to this drawing, in a case or housing 1 having an admission aperture 2 and a discharge aperture 3 for the exhaust gases there is arranged, in perfect contact with the casing, a series of sections of helical surfaces or vanes 4, 5, 6, 7 of alternately opposite pitch so that the gases admitted to opening 2 are compelled to first pass through a way, for instance left-handed, between helix 4 and the wall of casing 1 up to section 8, and then a right-handed thread way between helix 5 and wall of casing 1 up to section 9, and so forth, another left-handed thread way up to section 10 and a right-handed one up to section 11.

In the reversing sections 8, 9, 10 the gases moved with great velocity in a given rotatory direction are compelled to suddenly reverse rotation with difficulty which is the greater the higher is the velocity of the gases. Thereby a positive dynamic resistance to the movement of the fluid, i. e. exhaust gases, is created so that the latter, at last,

are discharged from orifice 3 with substantially uniform and silent flow.

For further improving the effect of the silencer it may be advantageous to place in front of section 11, i. e. between the last helix 7 and the exhaust 3, a disk 12 with helical blades (see also Fig. 2) with a turn opposite to that of helix 7. In this case the gases leaving the helix 7 still receive a last change of rotary direction before reaching exhaust 3.

As appears from the drawing, the helices 4, 5, 6, and 7 are supported on an axial shaft which, however, may also be omitted. Preferably the first turn 14 of helix 4 is welded to casing 1 so as to prevent axial shifting of the group of helices 15 in casing 1. Other known means may be used for fixing helices 4, 5, 6, and 7.

As appears from the drawing which, however, is not limitative, helix 4 is of a greater axial length than the subsequent helix 5, and so helix 5 to helix 6, and helix 6 to helix 7. The subsequent helices may also be of different pitch, diameter and length. Particularly, they may be substituted with helically wound tube sections consecutively welded together with alternately right and left-handed thread.

As is seen from Fig. 1, the radial section 15 of a spire of helix 4 is preferably concave, with the concavity turned to the entering gases in order to offer a sufficient mechanical resistance for 30 preventing deformation under pressure of the hot exhaust gases.

My present invention is here described and shown in a preferred modification in a purely illustrative, not limitative way, and any useful or necessary structural alterations may be applied thereto within the scope of the invention.

Having now particularly described and ascertained the nature of my said invention and in what manner the same is to be performed, I declare that what I claim is:

A silencer for internal combustion engines comprising a casing having an inlet and an outlet, a shaft extending longitudinally through said casing, a plurality of sections of helical vanes disposed along said shaft, the pitch of alternate sections being in opposite directions, so that a change of direction of rotation is imparted to the exhaust-gases from one section to the other, and the longitudinal extent of each section being successively smaller than that of the preceding section in the direction of the outlet.

GIORGIO BACCHETTI-RIGHETTI.
